(57) **CLAIM**

The ornamental design for a fly repellent fan, as shown and described.

DESCRIPTION

FIG. 1 is a front, right and top perspective view of a fly repellent fan showing my new design;

FIG. 2 is a rear, left and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view taken from circle 9 in FIG. 3;

FIG. 10 is a front, right and top perspective view thereof in another configuration; and,

FIG. 11 is a rear, left and bottom perspective view thereof in yet another configuration.

The dash-dash broken lines in the drawings depict the portions of the fly repellent fan that form no part of the claimed design.

The dot-dash broken lines in the drawings depict the boundaries of the partial enlarged views and form no part of the claimed design.

1 Claim, 11 Drawing Sheets
